UNITED STATES PATENT OFFICE.

FRANCES LORRAINE BONDS, OF IVA, SOUTH CAROLINA.

BEDPAN.

Application filed June 3, 1927. Serial No. 196,324.

This invention relates to a bed pan, designed primarily for use when giving an enema, but it is to be understood that, a bed pan in accordance with this invention, 5 can be employed for any purposes for which it is found applicable, and the invention has for its object to provide, in a manner as hereinafter set forth, an article of such class constructed and arranged where- 10 by an enema can be given in a conveniently and thoroughly efficient manner, at the same time affording a comfortable rest seat for the patient, as well as carrying off the douche solution without soiling the bedding.

15 Further objects of the invention are to provide, in a manner as hereinafter set forth, a bed pan which is comparatively simple in its construction and arrangement, strong, durable, compact, thoroughly efficient in its 20 use, conveniently arranged with respect to the patient, readily assembled, and comparatively inexpensive to manufacture.

With the foregoing and other objects in view the invention consists of the novel construction, combination and arrangement of parts, as hereinafter more specifically described and illustrated in the accompanying drawings, wherein is shown an embodiment 25 of the invention, but it is to be understood, 30 that changes, variations and modifications can be resorted to, which fall within the scope of the claims hereunto appended.

In the drawings wherein like reference characters denote corresponding parts 35 throughout the several views:

Figure 1 is a top plan view of a bed pan in accordance with this invention.

Figure 2 is a longitudinal sectional view thereof.

40 Figure 3 is a section on line 3—3 Figure 1 and further illustrating a collecting receptacle suspended from a discharge spout, the receptacle being shown in section.

A bed pan, in accordance with this in- 45 vention, is of substantially pear shape in outline whereby one end thereof will be of greater width than the other end, the larger end being the inner end and the smaller end the outer end. The pan can be constructed 50 of any appropriate length and width.

The pan includes a bottom 1 of pear shape outline and formed with rounded ends. Secured to the bottom 1 is the body portion 55 of the pan and which is of appropriate height. The body portion is referred to generally by the reference character 2, is

constructed of any suitable material and its bottom is crimped as at 3, to form a continuous groove 4 for the reception of the bottom 1. The crimp 3 overlaps the marginal portion throughout of the upper and lower faces of the bottom 1. That part of the body portion 2, above the crimp 3 is inset with respect to the edge of the bottom 1. The crimp 3 projects laterally with respect to the lower part of the body portion 2 and is coextensive with the latter. The top of the body portion 2 is formed with a laterally extending reinforcing bead 5 which is coextensive with the body portion. 60 The larger or inner end of the body portion 2, which is referred to by the reference character 6, is vertically disposed and the remaining part of the body portion 2 is outwardly inclined as indicated at 7. 65

The body portion 2 in proximity to its smaller or outer end, and in one side thereof, is formed with an opening 8, to the wall of which is secured an outwardly extending threaded outlet nipple 9, upon which is detachably secured the threaded inner terminal portion 10, of a discharge pipe 11, which at its outer end terminates in a depending, inclined, flaring spout 12. The pipe 11 is of any suitable length and carries 70 at its outer end a vertically disposed stop lug 13, positioned on the top of the pipe, and provides means for retaining the bail 14, of a receptacle or bucket 15 for receiving the douche solution from the spout 12. The lug 75 13 also provides means for positioning the receptacle or bucket 15 with respect to the discharge spout 12. The pipe 11 is of a 80 length as to extend from the bed. 85

Mounted upon the body portion 2, at the wider portion thereof, is a rest seat referred to generally by the reference character 16 and which consists of a body portion 17 depressed to depend into the body portion 2 and which is concaved in transverse section. The body portion 17 at the forward part thereof is formed with a cutout portion 18, preferably of substantially semi-oval contour and which provides a clearance so that access can be had to the parts 90 to be treated and further so that the douche solution can be discharged into the pan. The forward edge of the body portion 17 inclines from the outer ends thereof rearwardly towards the edge of the cutout portion 18. The marginal portion at the high 95 part of the body portion 17 is crimped to 100 105 110

provide a rim 19 of inverted U-shape in cross section and which opposes the inner face of the larger part 6 of the body portion and also opposes the bead 5. The rim 19 prevents the shifting of the rest seat from shifting lengthwise of the body portion 2, but will permit of removing the rest of the seat when desired.

Mounted on the top of the body portion 2, forwardly with respect to the rest seat 16, is a top member 20 of concave contour in transverse section and formed with a curved rear edge 21, which is spaced from the forward edge 22 of the seat 16. The edge 21 curves away from the edge 22. The marginal portion at the high part of the member 20 is formed with a rim 24 of inverted U-shape which opposes the inner face of the smaller or outer end 7 of the body portion 2, and also opposes the bead 5. The rim 24 prevents the shifting of the member 20 lengthwise of the body portion 2, but will permit of the removal of the member 20 when desired.

25 The seat rest 16 is detachably mounted on the body portion 2, so when it is removed the pan can be cleaned. In longitudinal section the top member 20 extends at a downward inclination from the high part 30 thereof, the latter being arranged at the outer end of the pan, to the rear end thereof. In longitudinal section the seat rest inclines downwardly from the high part thereof, which is at the rear end of the pan, to 35 the forward end of the seat rest. By this arrangement the top member 20 and the seat rest 16, in lengthwise section, incline in opposite direction with respect to each other, see Figure 2. The inclination of the top member 20 and seat rest 16 provides for any 40 of the douche solution to be conducted to the body portion 2 where it is discharged through the nipple 8.

The outer or smaller end of the body portion 2, is provided with a handle 23 so that the pan can be conveniently handled and hung up when not in use.

The construction and arrangement of the seat rest 16 and top member 20, as well as 50 the shape of the pan, will permit of an enema being given in a conveniently and thoroughly efficient manner, at the same time affording a comfortable seat rest for the patent, as well as carrying off the douche 55 solution.

It is thought the many advantages of a bed pan, in accordance with this invention, can be readily understood, and although the preferred embodiment of the invention is as 60 illustrated and described, yet it is to be understood that changes in the details of construction can be had which will fall within the scope of the invention as claimed.

What I claim is:

65 1. A bed pan comprising a bottom, an up-

standing body portion co-extensive therewith and connected thereto, a depressed seat rest mounted upon the sides and rear end of the body portion and of less length than the length of the latter, said rest having its 70 forward end cut out to provide a rearwardly extending clearance, a top member mounted on the sides and forward end of the body portion and of less length than the length of the latter, and a discharge pipe connected to 75 and communicating with said body portion.

2. A bed pan comprising a body portion of pear shaped outline, an upstanding body portion co-extensive with said bottom, connected thereto and of the same outline as 80 the outline of the bottom, a depressed seat rest mounted upon the sides and larger end of said body portion and of less length than the length of the latter, said seat rest of concave cross section and having its forward 85 end cut out to provide a rearwardly extending clearance centrally thereof, a top member mounted on the sides and smaller end of the body portion and of less length than the length of the latter, said top member 90 having its rear end spaced from the forward end of the seat rest, and a discharge pipe connected to one side of and communicating with said body portion.

3. A bed pan constructed in accordance 95 with claim 2, said body portion having its larger end vertically disposed and the remaining portion thereof flaring.

4. A bed pan constructed in accordance with claim 1, said body portion having its 100 rear end vertically disposed and the remaining portion thereof flared.

5. A bed pan of pear shaped outline having 105 extending across the larger portion of its top a depressed seat rest and across the smallest portion of its top a depressed top member, said member and seat rest spaced from each other, said seat rest having its forward end, centrally thereof, formed with a rearwardly extending clearance.

6. A bed pan constructed in accordance 110 with claim 5, said member and seat rest, in lengthwise section, inclining downwardly in opposite directions and each of concaved curvature in transverse section.

7. A bed pan comprising a bottom, an up-standing body portion co-extensive therewith and connected thereto, a forwardly extending, depressed seat rest mounted upon the sides and rear end of the body portion, of less length than the length of the latter and extending from one side to the other side of the body portion, said rest having its forward end cut out to provide a rearwardly extending clearance, a top member mounted on the sides and forward end of the body portion, of less length than the length of the latter and extending from one side to the other side of the body portion and having its rear end spaced from the 120 125 130

forward end of said seat rest, and a discharge pipe connected to and communicating with said body portion.

8. A bed pan comprising a bottom, an upward standing body portion co-extensive therewith and connected thereto, a forwardly extending, depressed seat rest mounted upon the sides and rear end of the body portion, of less length than the length of the latter, 10 said rest having its forward end cut out to provide a centrally disposed rearwardly extending clearance, a top member mounted on the sides and forward end of the body portion, of less length than the length of the latter and extending from one side to the other side of said body portion, said seat rest having its forward end inclining inwardly from each side thereto to said cut out portion and said top member having its rear 20 end inclining inwardly from each side towards its center, the inclination of the rear end of the top member being opposite to that with respect to the forward end of the seat rest.

25 9. A bed pan comprising a bottom, an up-

standing body portion co-extensive therewith and connected thereto, a forwardly extending-depressed seat rest mounted upon the sides and rear end of the body portion, of less length than the length of the latter 30 and extending from one side to the other side of said body portion, said rest having its forward end cut out to provide a rearwardly extending clearance, a top member mounted on the sides and forward end of the body portion, of less length than the length of the latter and extending from one side to the other side of the body portion and having its rear end spaced from the forward end of said seat rest, and a discharge pipe 35 connected to and communicating with said body portion, said member and seat rest, in lengthwise section, inclining downwardly in opposite directions with respect to each other and each of concave curvature in transverse 40 section at any point throughout its length.

In testimony whereof, I affix my signature hereto.

FRANCES LORRAINE BONDS.
